UNITED STATES PATENT OFFICE.

ARTHUR F. MARTEN, OF STORM LAKE, IOWA.

ENVELOP-SEALING MACHINE.

1,055,199.

Specification of Letters Patent.

Patented Mar. 4, 1913.

Application filed July 22, 1911. Serial No. 639,965.

To all whom it may concern:

Be it known that I, ARTHUR F. MARTEN, a citizen of the United States, residing at Storm Lake, in the county of Buena Vista 5 and State of Iowa, have invented new and useful Improvements in Envelop-Sealing Machines, of which the following is a specification.

This invention relates to machines for sealing envelopes, and it has for its object to produce a machine of this class of simple and improved construction whereby envelopes may be easily, quickly and effectively sealed by first having the flaps moved to an 15 open position, next having moisture applied to the gummed portions of the flaps, next having the flaps restored to a folded position and finally having the flaps compressed so as to cause the gummed portion of the 20 flap to adhere firmly to the body of the envelop.

With these and other ends in view which will readily appear as the nature of the invention is better understood, the same consists in the improved construction and novel arrangement and combination of parts which will be hereinafter fully described and particularly pointed out in the claims.

In the accompanying drawings has been 30 illustrated a simple and preferred form of the invention, it being, however, understood that no limitation is necessarily made to the precise structural details therein exhibited, but that changes, alterations and modifications within the scope of the claims may be resorted to when desired.

In the drawings.—Figure 1 is a side elevation of a machine constructed in accordance with the invention. Fig. 2 is a top plan view of the same. Fig. 3 is a side elevation, showing the side of the machine opposite to that shown in Fig. 1. Fig. 4 is a vertical transverse sectional view taken on the line 4—4 in Fig. 1. Fig. 5 is a front elevation. 45 Fig. 6 is a sectional detail view taken on the line 6—6 in Fig. 5. Fig. 7 is a sectional detail view taken on the line 7—7 in Fig. 3.

Corresponding parts in the several figures are denoted by like characters of reference. 50 The bed or base 1 of the improved machine, which is preferably provided with feet or supporting members 2, 2, has a vertically disposed longitudinal wall or web 3 at the forward end of which is formed an upwardly and forwardly extending portion 55 constituting an arm 4 upon which the en-

velops that are to be operated upon may be hung or suspended by means of their flaps, as indicated. Rising from the base 1 adjacent to the wall or web 3 is a second wall portion 5, the latter being disposed in substantially parallel relation to the wall portion 3, and a narrow space 6 being left therebetween, as indicated, for the passage of the envelopes.

Supported upon the outer face of the arm 4, adjacent to the rear end of said arm, is a water box or well 7 having a downwardly extending flange 8 at its outer end, said flange serving in conjunction with the arm 4 to afford bearings for a shaft 9 having a crank 10 whereby it may be rotated. Supported in bearings at the upper edge of the well 7 is a moistening roller 11 which may be constructed of metal covered with absorbent material, such as cloth, it being desired, however, to be understood that the said roller may be constructed of any suitable material and that the covering may be dispensed with, if preferred. One of the 80 journals of the roller 11 carries a band wheel 12 which is connected by a belt or band 13 with a wheel or pulley 14 upon the crank shaft 9 from which motion may thus be transmitted to the roller 7 at any desired 85 rate of speed which may be gaged by the proportionate sizes of the wheels or pulleys 12 and 14. It is preferred, however, that the moistening roller 11 be driven at a surface speed somewhat exceeding the speed at 90 which the envelopes are moved by means to be hereinafter described.

The arm 4 is provided with a lateral extension 15 having a downturned flange portion 16 lying adjacent to the outer face of the arm 4 and serving to gradually lift or open the flaps of envelopes guided over said arm until the flaps rest upon the lateral extension 15 which forms a table or support for the flaps. Said table has a slot 17 through which the moistening roller projects, and upon the table or supporting member 15 adjacent to the outer edge thereof is a cap plate 18 secured by fastening means, such as a set screw 19, said cap plate being spaced from the support or table and provided with an upwardly curved portion or dome 20 which is concentric with the surface of the moistening roller from which it is slightly spaced, as shown. The cap plate 18 is provided with a depending lug 18a lying adjacent to the outer face of the arm 4.

and serving as a guide to retain the body of the envelop in an approximately vertical position. The function of the plate 18 is to hold the flaps of the envelops in contact with the surface of the moistening roller from which, however, said presser plate is sufficiently spaced to avoid wetting or soiling the same. By forming the well with the downwardly extending flange 8, the main 10 driving shaft 9 which has a bearing in said flange may be positioned entirely beneath the well, and the band 13 by which motion is transmitted to the moistening roller will be positioned adjacent to one of the side walls 15 of the well where it will be out of the way of possible interference with the material to be fed or with the hands of the operator.

A plurality of pairs of feed rollers 21, 22 are supported, respectively, adjacent to the 20 wall portions 3 and 5, said wall portions being provided with slots 23 to permit the feed rollers to contact with each other. The rollers 21 associated with the wall member 3 are mounted upon vertical shafts 24, the 25 lower ends of which are journaled in the base 1, said shafts being additionally supported by means of brackets 25 extending from the wall member 3, and the rollers are mounted on the shafts above the bearing 30 brackets 25 so as to be in no wise obstructed by the bearings or by any portion of the frame structure. The feed rollers 22 are supported for rotation upon resilient arms 26 which are secured by fastening members, 35 such as screws 27, upon the wall member 5. The rollers 22 will thus be capable of yielding so as to accommodate themselves to any thickness of envelops passing between said rollers and the mating rollers 21. For the 40 purpose of driving the rollers 21 the lower ends of the shafts 24 are equipped with gear wheels 28, some of which receive motion directly from a gear wheel 29 upon the lower end of a vertical shaft 30 having at its 45 upper end a bevel pinion 31 meshing with a bevel pinion 32 upon the crank shaft 9. The said crank shaft thus serves not only to drive the moistening roller, but also the shaft 30 having the gear wheel 29 meshing 50 with the gear wheels 28 of two proximate feed roller carrying shafts 24 which will thus be driven in the proper direction. Motion is transmitted from the gear wheel 28 upon one of the shafts 24 to the remaining 55 feed roller carrying shafts 24 by means of idlers 33 which are supported for rotation upon or adjacent to the underside of the base.

An arm 34 extending upwardly from the 60 wall member 5 adjacent to the rear end of the latter is provided with a downturned flange 35 formed with a flaring lip portion 36 for the purpose of engaging the flaps of the envelops to turn said flaps down upon 65 the bodies of the envelops. The arm 34 car-

ries a resilient bracket 37 provided with bearings supporting one of the sealing rollers 38, the other sealing roller 39 being supported upon a shaft 40, the lower end of which is supported for rotation in the base 1, said shaft having an additional bearing 70 in a bracket 41 extending from the wall member 3. The lower extremity of the shaft 41 is equipped with a pinion 42 meshing with one of the idlers 33. 75

In the operation of this machine, the envelops that are to be sealed are hung or suspended upon the upper end of the arm 4 and are thence pushed or fed manually in the direction of the moistening roller. The 80 flange member 16 serves to turn up the flap of the envelop until it rests upon the table or supporting member 15 being guided beneath the cap plate 18. By this time the envelop will be engaged by the first set of 85 feed rollers and will now be fed positively in a rearward direction, the gummed portion of the flap being moistened by contact with the roller 11 which, as previously stated, is preferably operated at a surface 90 speed slightly exceeding the speed of the feed movement of the envelop. The flap having been moistened, the envelop is now fed rearward between the several sets of feed rollers the lower edge of the envelop being 95 guided between the parallel walls or guide members, which prevent distortion of the envelop, until the flap is engaged by the flange member 35 having the flaring lip portion 36, whereby the flap is turned down 100 flat upon the body of the envelop. The latter now passes between the sealing rollers which are positioned to engage the flap on one side and the front face of the envelop on the other side, compressing the flap upon 105 the body of the envelop and completing the sealing operation.

As will be readily understood from the foregoing description taken in connection with the drawings hereto annexed, envelops 110 may be sealed very rapidly and efficiently by the improved device which is simple in construction and capable of being manufactured and marketed at a moderate price.

Having thus described the invention, what 115 is claimed as new, is:—

1. In an envelop sealing machine, a base, spaced wall members rising therefrom in approximate parallel relation, one of said wall members being provided with an upwardly extending envelop guiding and supporting arm, and said wall members being provided with slots, feed rollers adjacent to the respective wall members and contacting through the slots therein, resilient supporting means for the feed rollers adjacent to one wall member, means for positively driving the feed rollers adjacent to the other wall member, flap-opening and moisture applying means, and means adjacent to the 130

rear ends of the wall members for closing the flaps.

2. In an envelop sealing machine, a base, wall members rising therefrom in approximate parallel relation and spaced for the passage of envelopes therebetween, said wall members being provided with slots, feed rollers adjacent to the wall members and contacting through the slots therein, resilient supporting means for the feed rollers adjacent to one wall member, and means for positively driving the feed rollers adjacent to the other wall member.

3. In an envelop sealing machine, a base, wall members rising therefrom in approximate parallel relation and spaced for the passage of envelopes therebetween, said wall members being provided with slots, feed

rollers adjacent to the wall members and contacting through the slots therein, sealing 20 rollers supported adjacent to the rear ends of the wall members, resilient supporting means for the sealing and feed rollers adjacent to one wall member, a water well, a moistening roller partly submerged therein, 25 a driven shaft, and means for transmitting motion from said shaft to the moistening roller and to the sealing and feed rollers adjacent to the other wall member.

In testimony whereof I affix my signature 30 in presence of two witnesses.

ARTHUR F. MARTEN.
